UNITED STATES PATENT OFFICE.

AMRY M. CURRY, OF PIONEER, TEXAS.

PORATABLE BATH-CABINET.

1,125,008.

Specification of Letters Patent.

Patented Jan. 12, 1915.

Application filed March 13, 1914. Serial No. 824,494.

To all whom it may concern:

Be it known that I, AMRY M. CURRY, a citizen of the United States, residing at Pioneer, in the county of Eastland and State of Texas, have invented new and useful Improvements in Portable Bath-Cabinets, of which the following is a specification.

The invention relates to a bath cabinet, and more particularly to the class of portable bath cabinets.

The primary object of the invention is the provision of a cabinet wherein a bath tub is supported on the swinging door of the inclosure so that when the latter is open the tub will be in position for use for bathing purposes.

Another object of the invention is the provision of a cabinet of this character wherein the same can be moved from one place to another, and the tub when in position for use will be curtained, the curtain being foldable when the cabinet is closed so that the tub and curtain will be hidden from view, thus giving the cabinet the appearance of an ordinary wardrobe.

A further object of the invention is the provision of a cabinet of this character which is extremely simple in construction, readily and easily portable from one point to another, neat and attractive in appearance, and inexpensive in manufacture.

With these and other objects in view, the invention consists in the construction, combination and arrangement of parts as will be hereinafter fully described, illustrated in the accompanying drawing, and pointed out in the claim hereunto appended.

In the drawings: Figure 1 is a perspective view of the cabinet constructed in accordance with the invention, the same shown closed. Fig. 2 is a side elevation thereof, showing the tub in position for use and curtained, the curtain being partly broken away. Fig. 3 is a vertical longitudinal sectional view through the cabinet when open. Fig. 4 is a similar view, showing the cabinet closed. Fig. 5 is a top plan view.

Similar reference characters indicate corresponding parts throughout the several views in the drawings.

Referring to the drawings in detail, A designates a cabinet formed with a doorway 10 in its front wall, which is closed by means of a swinging door 11, the same connected to the body of the cabinet A by

means of hinges 12 which are fastened to the lower edge of the door so that the same can be lowered into horizontal position when open.

Secured to the inner face of the door 11 are intermediate and outer supporting strips 13 and 14 respectively, said strips being arranged transversely of the door, and on which rests a bath tub 15 which is of any ordinary well-known construction, having a waste pipe 16 extending through the door 11 to the outer side thereof, the opening in the door for the waste pipe being normally closed by means of a shutter or cover plate 17 swingingly connected to the door. The waste pipe 16 is adapted to be fitted with a stopper plug 18 of the ordinary well-known construction connected to a retaining chain 19 fixed to the tub 15 in any suitable manner.

The tub 15 is secured to the door 11 by means of securing members 20 which are fastened thereto and to the door. Formed in the door 11 at the outer side thereof is a recess 22 in which is adapted to be received a leg 21 which serves to support the said door 11 in horizontal position when open. The bottom of the cabinet A carries at the corners casters 23 which permit the rolling of the same from one point to another, thereby rendering the cabinet portable.

Fixed to the back wall of the cabinet A near the top thereof is a flexible canopy covering 24 which serves as a curtain, and is also connected to a prop frame 25 connected for swinging movement by means of hinges 26 to a cross bar 27 secured to one end of the tub 15, the prop frame being provided with swinging brace legs 28 which are adapted to engage the notches 29 formed in the upper edge of the casing for the tub 15 so as to hold the frame upright, and thereby extend the canopy covering 24 and hold it at the proper elevation above the tub 15 when ready for use.

On disengaging the leg 28 from the notches 29 the frame 25 can be folded inwardly onto the tub 15 so that when closing the door 11 the said tub and curtain therefor will be concealed within the cabinet A. The door 11 when swung to closed position gives the cabinet the appearance of an ordinary wardrobe or other similar article of furniture. When it is desired to discharge the water from the tub 15 it is nec-

sary to attach a rubber hose to the waste pipe 16, which will convey the water therefrom to any suitable point, the plug 18 being removed from the waste pipe when the 5 water is to be discharged from the tub.

In one side wall of the cabinet is mounted 10 a door 30, which is connected thereto for opening movement so that a person can enter the cabinet when the tub has been lowered to horizontal position, thereby enabling a person to prepare for a bath. Within the cabinet is arranged a seat 31 which can be occupied by the person preparing for a bath, and within this cabinet can be arranged any 15 suitable equipment for the hanging of cloths, and for holding soap, towels or the like.

From the foregoing it is thought that the construction and manner of use of the device will be clearly understood, and therefore a more extended explanation has been omitted.

What is claimed is:—

The combination with an inclosure having

Copies of this patent may be obtained for five cents each, by addressing the "Commissioner of Patents, Washington, D. C."

a vertically swinging door section, of a rest 25 secured to the inner face of the door section, a tub mounted within said rest, uprights 30 swingingly connected to the rest at the outer end of the tub, two-part hingedly connected braces pivoted to the uprights and engageable with the rest to prevent the inward folding of the said uprights, a flexible covering having its top stretch connected within the inclosure at the upper end thereof and also connected with the uprights, the side 35 and end stretches of the covering having their free edges terminating in a plane with the door section when in horizontal position to entirely conceal the tub, and foldable means on the door section to hold the same 40 in true horizontal position when open.

In testimony whereof I affix my signature in presence of two witnesses.

AMRY M. CURRY.
